CLAIM

I claim the ornamental design for connector assembly, as shown and described.

DESCRIPTION

FIG. 1 is a front elevational view of a first embodiment of a connector assembly in accordance with my design;
 FIG. 2 is a left side elevational view thereof;
 FIG. 3 is a rear elevational view thereof;
 FIG. 4 is a right side elevational view thereof;
 FIG. 5 is a bottom plan view thereof;
 FIG. 6 is a top plan view thereof; and,
 FIG. 7 is a perspective view thereof.

The broken lines shown represent portions of the connector assembly in which the design is embodied that form no part of the claim to design.
